(57) **CLAIM**

The ornamental design for a hose connector for medical use as shown and described.

DESCRIPTION

FIG. 1 is a perspective view showing a hose connector for medical use;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict portions of the hose connector for medical use and form no part of the claimed design.

1 Claim, 3 Drawing Sheets
